UNITED STATES PATENT OFFICE.

EDMUND RANDOLPH, OF PORTLAND, OREGON.

ROTARY GRAVITY-MACHINE FOR SEPARATING AND CONCENTRATING PRECIOUS METALS.

1,247,717.

Specification of Letters Patent. Patented Nov. 27, 1917.

Application filed December 19, 1916. Serial No. 137,822.

To all whom it may concern:

Be it known that I, EDMUND RANDOLPH, a citizen of the United States, residing at Portland, in the county of Multnomah and 5 State of Oregon, have invented a new and useful Rotary Gravity-Machine for Separating and Concentrating Precious Metals, of which the following is a specification.

The present invention appertains to apparatus for separating and concentrating precious metals, such as gold and platinum, and it is the object of the invention to provide a novel and improved rotary gravity machine for the recovery of such metals 15 from sand and dirt and adapted especially for use in placer mining.

The invention has for its object the provision in a machine of that character of novel construction, to enhance the utility 20 and efficiency thereof, the machine being comparatively simple, compact and inexpensive in construction.

A further object of the invention is the provision of a rotary machine of that character having novel means for conducting the water, sand, dirt and lighter materials from one compartment to another, so that the heavier metals or concentrates accumulate within said compartments from which they 30 can be discharged from time to time.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:—

Figure 1 is a plan view of the machine, looking downwardly at right angles with 45 the receptacle.

Fig. 2 is a cross section taken on the line 2—2 of Fig. 1.

Fig. 3 is a vertical longitudinal section taken on the line 3—3 of Fig. 1.

50 Fig. 4 is a perspective view of the shield.

Fig. 5 is a fragmental perspective of one of the rotary members.

In carrying out the invention, there is provided an inclined trough-shaped receptacle 1 supported by suitable legs 2 and of

substantially semicircular cross section. The receptacle is provided with a longitudinal series of transverse partitions 3 defining transverse compartments 4. The lower end 5 of the receptacle is arranged at an obtuse angle with the bottom of the receptacle, and is provided with an extension 6 projecting at an obtuse angle therefrom and providing a hopper into which the water and dirt or sand is fed. The receptacle is provided with discharge apertures 7 in its bottom at the lowermost portions of the compartments 4, and suitable valves 8 are seatable upwardly to normally close said apertures. The valves are carried by levers 9 fulcrumed, as at 10, 70 to the receptacle. The free arms of the levers 9 are movable along stems 11 projecting from the receptacle, and nuts 12 are threaded upon said stems for limiting the movements of the levers 9. The free arms 75 of said levers can readily be pressed toward the receptacle for unseating the valves to enable the concentrates or heavier precipitates to be discharged through the apertures from time to time, for testing whether the sand or dirt being worked is of a paying quality. The levers 9 are pressed by springs 13 to close the valves when the levers are released.

A cross piece 14 is mounted within the receptacle, adjacent to its lower end, for supporting an upstanding shield 15. A bearing 16 is secured to the shield adjacent to the lower edge thereof and is adapted to be received by an upwardly opening slot or notch 90 17 with which the cross piece 14 is provided, the bearing 16 having grooves 18 for engaging the side edges of the notch 17 for holding the bearing in place, as well as the shield 15, with the lower edge of the shield overlapping the cross piece 14 and coöoperating with the extension 6 to provide the feed hopper at the lower end of the receptacle. The shield 15 prevents the material which is dumped into the hopper from falling past 100 said shield over the cross piece 14.

The bearing 16 has a socket 19 in which the lower end of an inclined shaft 20 is journaled, said shaft being inclined similarly to the receptacle 1 and extending 105 longitudinally across the partitions 3. The shaft 20 is seated near its upper end in a notched or slotted bearing 21 carried by a cross piece 22 in turn carried by the upper end of the receptacle 1. By withdrawing 110

the shield 15 and bearing 16 from the cross piece 14, the shaft 20 can be lifted from the receptacle for purpose of cleaning, repairing or examining the device. The shaft 20 can 5 be rotated in any suitable manner, such as by means of a pulley wheel 23 secured upon the upper terminal thereof.

Mounted upon the shaft 20 at spaced longitudinal points, are a series of disks 24, one 10 for each compartment 4, said disks being disposed in inclined planes with their lower portions within the compartments 4 and their margins working near the walls of the receptacle. The disks 24 are provided upon 15 their upper faces adjacent to the upper walls of the compartments 4 with spirally extending flanges 25 arranged at right angles with the disks, and each disk can have any suitable number of these flanges 20 which provide spiral V-shaped troughs. The outer terminals of the flanges 25 terminate near the edges of the disks 24. The inner ends of the flanges 25 terminate between the disks 24 and annular plates or 25 ring 26 associated with the disks at the upper sides thereof and working below the respective partitions 3. Extending from the inner edges of the rings 26 are flared annular flanges or funnels 27 overhanging 30 the respective partitions for delivering the material from one compartment to another. The disks 24 have hubs 28 slipped upon the shaft 20, and said shaft 20 has a collar 29 adjacent to its lower end against which the 35 hub 28 of the lowermost disk seats. The hub 30 of the uppermost disk carries a set screw 31 for holding it fixed upon the shaft, and the hubs of the disks are provided with interlocking lugs or portions 40 32 preventing the relative rotation of the disks, whereby they all rotate as a unit with the shaft 20. When the shaft is removed and the set screw 31 loosened, the disks can be readily slid off of the shaft, providing 45 that the pulley wheel 23 is removed.

Disposed within the openings of the rings 26 and the openings surrounded by the inner ends of the flanges 25 are annular sets 50 of helical blades 33. These blades extend helically from the disks 24 in an upward direction, and extend from the rings 26 to the hubs 28. Certain of the flanges 25 have their inner ends extended, as at 34, to the ends of the blades 33, and the other flanges 55 25 terminate short of said blades. Any number of flanges of either form can be used, those flanges which have the extensions 34 being of the same number as the blades 33.

60 A chute or apron 35 is secured to the uppermost partition or upper end 3 of the receptacle and is overlapped by the flange or funnel 27 of the uppermost disk 24 for the discharge of the material delivered from the 65 upper compartment.

The disks 24 are provided with agitating blades or vanes 36 projecting from the edges thereof in annular series, and said blades or vanes 36 have their terminals bent at obtuse angles whereby said blades 70 are substantially helical for agitating the material transversely of the disks and longitudinally of the receptacle 1, the blades 36 being so arranged that when the disks 24 are rotated in the direction of the arrow in 75 Fig. 2, the blades 36 tend to force the material upwardly within the respective compartments.

The operation of the machine is as follows: The sand or dirt is delivered with 80 the water into the hopper at the lower end of the receptacle, and the shaft 20 is rotated in the proper direction. The blades or vanes 36 of the lowermost disk agitate the material and force it upwardly so that 85 the water and lighter materials are scooped up from the upper portions of the compartment bottoms by the lower ends of the flanges 25 of the lowermost or first disk, and as the disk rotates, the water and material scooped up by the flanges 25 is carried toward the center of the disk, being raised from the lower portion of the first compartment. The material is thus raised to the blades 33 of the first disk, and said 90 blades will shed the material through the opening of the first ring 26, from which the material will run down the flange or funnel 27 over the partition 3 between the first and second compartments, the material thus being carried from the first into the second 95 compartment. This operation is continued from one compartment to the other the length of the receptacle, the lighter materials and water thus being carried upwardly and finally discharged from the chute 35, and the heavier metals, such as 100 gold and platinum, settling within the lowermost points of the compartments as concentrates. Tests can be made from time to 110 time by opening the valves 8 to determine whether the sand or dirt being worked is of a profitable nature, and the compartments are cleaned out from time to time at suitable intervals. Thus, when clean up time 115 comes, the flow of material into the hopper is stopped, and the machine is left running for a sufficient length of time to clean out all the excess lighter materials, the water still flowing into the machine to assist in 120 cleaning it out, leaving only the concentrates and water so that they can be readily discharged by opening the valves 8. The gold and platinum and other precious metals 125 can be caught in a suitable trough or receptacle.

Having thus described the invention, what is claimed as new is:

1. A machine of the character described embodying a compartment having an in- 130

clined bottom, and a rotatable member working within said compartment and having means at its margin for working the materials upwardly on said bottom, said member 5 having means leading from its margin toward its center for raising the lighter materials from the upper portion of said bottom to discharge them.

2. A machine of the character described 10 having a series of compartments with inclined bottoms, and a plurality of rotatable members rotating as a unit and working in the respective compartments, said members having marginal portions for working the 15 materials upwardly on said bottoms, and said members having means extending from their marginal to their central portions for raising the lighter materials from the upper portions of said bottoms to discharge the 20 lighter materials into the next upper compartments.

3. A machine of the character described 25 embodying an inclined receptacle having transverse partitions providing compartments having inclined bottoms, disks rotatable within said compartments, agitating means carried by the edge portions of said disks for working the lighter materials upwardly on said bottoms, means carried by 30 the disks for raising the materials from the upper portions of said bottoms, and means carried by the disks for discharging the materials raised by the second mentioned means into the adjacent compartments.

35 4. A machine of the character described embodying an inclined receptacle having transverse partitions providing compartments having inclined bottoms, an inclined shaft, disks carried by said shaft and working 40 in said compartments, agitating means carried by the edge portions of said disks for moving the materials upwardly upon the bottoms of said compartments, means carried by said disks for raising the materials 45 from the upper portions of said bottoms, and means carried by the disks for discharging the raised materials from the second mentioned means into the next upper compartments.

50 5. A machine of the character described embodying an inclined compartment having an inclined bottom, an inclined rotatable disk working within said compartment, blades carried by the edge portion of said 55 disk for working the materials upwardly on the bottom of said compartment, and spiral

portions carried by said disk adjacent to the upper wall of said compartment for raising the materials from the upper portion of said bottom.

60

6. A machine of the character described embodying a compartment, a rotatable disk working therein, spiral flanges carried by the disk for scooping up and raising the materials, a flared flange associated with the 65 inner ends of said flanges and overhanging one wall of said compartment, and blades carried by the disk centrally of the spiral flanges for directing the materials from the inner ends of the spiral flanges over said 70 flared flange.

7. A machine of the character described 75 embodying an inclined receptacle having transverse partitions providing concentrat- 80 ing compartments and having lower outlet means for said compartments, an inclined shaft, disks carried by said shaft working in the compartments, agitators carried by the edges of the disks for working the materials upwardly within the lower portions 85 of said compartments, spiral flanges carried by the upper faces of said disks for scoop- 90 ing up and raising the materials, flared flanges associated with the inner ends of said spiral flanges and overhanging the partitions for delivering the materials into the next upper compartments, and blades carried by the disks centrally of the spiral flanges for directing the materials from the inner ends of said spiral flanges over said 95 flared flanges.

8. A device of the character described 95 embodying an inclined receptacle having a series of compartments and a cross piece near its lower end, said cross piece having a seat, 100 a bearing fitted in said seat, a shield carried by said bearing and co-operating with the lower end of the receptacle to provide a feed hopper, an inclined shaft having its lower end journaled in said bearing, and a device 105 carried by said shaft working in said compartments for raising the materials therein and delivering them into the next upper compartments.

In testimony that I claim the foregoing 105 as my own, I have hereto affixed my signature in the presence of two witnesses.

EDMUND RANDOLPH.
